FOLDING MACHINE

Karl F. Riese, Minneapolis, Minn.

Application July 20, 1936, Serial No. 91,475

11 Claims. (Cl. 270—94)

My invention relates to folding machines and has for an object to provide a machine by means of which sheets of paper, such as letters, circulars, bills, invoices and the like may be readily and quickly folded for the purpose of insertion in envelopes.

Another object of the invention resides in providing a machine which will produce the desired results quickly and positively.

10 A still further object of the invention resides in providing a folding machine in which the sheets are first creased and thereafter folded.

Another object of the invention resides in providing a machine in which the folded sheets are 15 pressed together so as to become relatively flat to permit of easy insertion into the envelopes.

A feature of the invention resides in providing an extremely compact machine which will occupy a minimum amount of space.

20 An object of the invention resides in providing a machine in which all of the operations are automatically performed.

Another object of the invention resides in providing a folding machine in which creasing of 25 sheets is accomplished by scoring rolls.

A still further object of the invention resides in providing a folding machine in which folding of creased sheets is accomplished by means of a table on which the folded sheets are deposited 30 together with two pivoted blades having their axes in close proximity to said table and movable from extended positions to positions overlying said table, whereby the portions of the sheets adjacent the score marks thereon are successively 35 folded into overlying position.

Another object of the invention resides in utilizing one of the scoring rolls as a part of the pressing mechanism.

A still further object of the invention resides 40 in reversing the travel of the sheet through the machine so as to reduce the length of the machine.

Other objects of the invention reside in the novel combination and arrangement of parts and 45 in the details of construction hereinafter illustrated and/or described.

In the drawings:

Fig. 1 is a plan view of a folding machine illustrating an embodiment of my invention.

50 Fig. 2 is a longitudinal sectional view taken substantially on line 2—2 of Fig. 1.

Fig. 3 is an end elevational view of the structure shown in Fig. 1.

Fig. 4 is a transverse sectional view taken on 55 line 4—4 of Fig. 1.

Figs. 5 to 10 are diagrammatic views showing the various steps through which the paper passes during the folding thereof.

My invention consists generally of a creasing mechanism indicated by the reference numeral 5 A and to which sheets of paper arranged in a magazine B are fed by means of a feed mechanism C. The sheets upon leaving the creasing mechanism are delivered to a folding mechanism D which folds into overlying positions the portions of the sheet formed by the creases. A second feed mechanism E moves the folded sheets from the folding mechanism D to a pressing mechanism F from which the sheets are delivered into a receiver G. The various mechanisms 10 of the invention are carried by a framework indicated in its entirety by the reference numeral H. These various parts of the invention will now be described in detail.

The framework H consists of two longitudinal 20 frame members 15 and 16 which are cast in the desired form to support the various parts of the invention. These castings are constructed with legs 17 which depend therefrom and which have rubber feet 18 attached to the lowermost portions of the same. The framework rests upon a table or other surface upon which the machine is supported through the feet 18. These feet are preferably formed of rubber and hold the entire machine from movement during the operation 25 thereof. The two frame members 15 and 16 are held in spaced relation by means of four rods 21, 22, 23 and 24. These rods are reduced in diameter at their ends and threaded to receive nuts 25 which clamp the frame members 15 and 16 30 against the shoulders formed on the ends of said rods. Such construction forming no particular 35 feature of the invention has not been shown in detail in the drawings.

The creasing mechanism A includes two scoring 40 rolls 26 and 27 which are mounted upon a shaft 28. These rolls are formed with V shaped ridges 29 which are adapted to enter V shaped grooves 31 in complementary scoring rolls 32 and 33 mounted on a shaft 34. The shaft 28 is journaled in two bearings 35 and 36 mounted in the frame members 15 and 16. This shaft is held from endwise movement within said bearings by means of a sprocket wheel 37 attached to the said shaft exteriorly of the frame member 15 by 50 means of a set screw 38 and by means of a collar 39 similarly attached to said shaft upon the other side of said bearing 35 by means of a set screw 41. The two score rolls 26 and 27 may be moved axially along the shaft 28 and are held in ad- 55

justed position thereon by means of thumb-screws 42 and 43.

The shaft 34 is supported in a manner to permit of movement of said shaft toward the shaft 5 28 to effect pressure between the rolls 32 and 33 and the complementary rolls 26 and 27. This is accomplished as follows: Upon the inner surfaces of the two frame members 15 and 16 are provided spaced guides 44. The facing surfaces of these 10 guides are accurately milled to form ways along which two bearing blocks 45 and 46 may slide. These bearing blocks are constructed with bearings 47 in which the shaft 34 is rotatable. The blocks 45 and 46 are held in position within said 15 ways by means of plates 48 which are secured to the guides 44 by means of machine screws 49. It can readily be comprehended that when the blocks 45 and 46 are urged upwardly, the rolls 32 and 33 are urged into engagement with the 20 rolls 26 and 27, forcing the V shaped ridges 29 of said last named rolls into the grooves 31 of the rolls 32 and 33.

For the purpose of sliding the bearing blocks 45 and 46 upwardly, two levers 51 and 52 are 25 employed. These levers are pivoted on a shaft 53 which is attached to the frame members 15 and 16. Said levers are constructed with heads 54 which engage the under surface of the blocks 45 and 46. The free ends of said levers which 30 are designated by the reference numerals 57 and 58 are urged downwardly by means of compression coil springs 61 and 62. These coil springs encircle bolts 63 which are attached to a cross 35 bar 64 secured to the frame members 15 and 16. Nuts 64 threaded on the ends of these bolts limit the downward movement of said levers. It can 40 readily be comprehended that when the said portions 57 of said levers are urged downwardly through the springs 61 and 62 that the blocks 45 are urged upwardly and pressure applied between the two pairs of scoring rolls.

For the purpose of illustration, a stack of sheets has been shown in Fig. 1 which is indicated in its entirety by the reference numeral 65. The 45 individual sheets in the stack are designated by the reference numeral 66 and the uppermost sheet by the reference numeral 67. The stack of sheets 65 is supported by the magazine B. This magazine is constructed with a bottom 68 disposed considerably below the points of tangency of the scoring rolls. This bottom is constructed from sheet metal with laterally extending flanges 70 which are secured to the frame members 15 and 16 by means of screws 80. At the forward end of 50 this bottom is provided an upturned lip 69, the leading edge 71 of which is in close proximity to the points of tangency of the scoring rolls. The paper sheets 66 carried by the magazine are fed one at a time from the stack 65 and the forward edges thereof engage the lip 69 and are moved upwardly to a position where the same may be grasped by the scoring rolls and fed through the said rolls through the friction resulting due to the pressure applied to the rolls 32 and 33.

55 The sheets 66 are held in position laterally by means of two side register gauges 72 and 73 which rest upon the bottom 68. These gauges are provided with brackets 74 projecting outwardly therefrom through which bolts 75 extend. Bolts 70 75 further extend through laterally positioned slots 76 in the bottom 68, whereby adjustment of the gauges 72 and 73 laterally of the magazine B may be had. The two gauges 72 and 73 are constructed with friction pads 77 which are 75 mounted on leaf springs 78 attached to the said

gauges by means of rivets 79. These pads may be constructed of rubber, leather or some other suitable material and press against the edges of the sheets 66, which prevents all of the sheets being removed from the stack at one time when the feed mechanism C is in operation. Tension on the springs 78 may be procured by means of adjusting screws 81 best shown in Fig. 1 which pass through said leaf springs and are threaded into the gauges 72 and 73.

10 For controlling the longitudinal position of the stack 65 in magazine B an end gauge 185 is employed. This end gauge is constructed with a bracket 186 similar to that of the gauges 72 and 73 through which a bolt 187 extends. Bolt 187 15 also passes through a slot 188 in the bottom 68 which runs longitudinally of the device and is disposed medially of the lateral edges of said bottom. By means of this construction the position of the gauge 185 may be adjusted at will.

20 The feed mechanism C includes a shaft 82 which is journaled in bearings 83 mounted in the two frame members 15 and 16. This shaft has secured to it two upstanding arms 84 and 85 which are constructed with bosses 86 rigidly secured to said shaft by means of pins 87. These two arms rotatably support another shaft 88 parallel to the shaft 82, which latter shaft is constructed with reduced ends 89 mounted for rotation in the two arms 84 and 85. Nuts 91 screwed 25 upon the ends of said shaft hold the shaft properly positioned with respect to said arms and prevent the arms from spreading at their upper ends.

25 The feed mechanism C further includes a feed roller 92 which is provided with a shaft 93 rotatably mounted in a fork 94. The roller 92 is constructed of rubber or some other suitable material having a suitable friction surface adapted to frictionally engage the uppermost sheet and feed the same toward the creasing device A. The shaft 40 93 is mounted in slots 95 in the fork 94 so that said roller 92 may move toward and from the cross bar 96 of said fork. Attached to the cross bar 96 (Fig. 5) is a blade 97 which is adapted to engage the surface of the roller 92. An arm 98 is 45 attached at one end to the cross bar 96 of fork 94 and at its other end is secured to a head 99 which is drilled to receive the shaft 88 which passes through the same. This head is tapped to receive a set screw 101 by means of which the 50 head 99 may be rigidly secured to the shaft 88. It will readily be seen that when the arms 84 and 85 are moved in a clockwise direction, as viewed in Fig. 2, that the fork 94 is pulled away from the roller 92, the shaft 93 of which slides in the slots 55 95. This frees the blade 97 from the periphery of the roller 92, permitting said roller to rotate freely. When the arms 84 and 85 are moved in a counter-clockwise direction, fork 94 is urged 60 toward the roller 92 and the blade 97 brought 60 into contact with the surface of said roller. This restrains rotation of said roller and the surface thereof engages the uppermost sheet 67, moves said sheet forwardly, causing the leading edge thereof to ride along the lip 69 and to be fed in 65 between the two sets of scoring rolls.

65 The paper on leaving the creasing device A is deposited on a table 102 forming a part of the folding mechanism D. Table 102 is constructed from sheet metal being provided with flanges 103 70 which are attached to the two frame members 15 and 16 by means of screws 204. Mounted on the table 102, are four bearings 104 and 105 which are attached to said table by means of screws 106 and 107. In the bearings 104 is journaled a shaft 108 75

and in the bearings 105 is journaled a shaft 109. The shaft 108 has attached to it a blade 111 which is adapted to swing from a position parallel to said table and in close proximity thereto to a position extending outwardly from said table. The shaft 109 has attached to it a similar blade 112 which is movable in the same manner as blade 111. The blades 111 and 112 are normally supported in upwardly extending diverging relation, as shown in Figs. 5 to 10. For this purpose, two sheet metal supports 113 and 114 are employed which are attached to the table 102 and which extend upwardly above the blades 111 and 112 and form guides for guiding the creased sheet in position upon the table 102 and between the blades 111 and 112.

The creased sheet, as previously stated, is deposited upon the table 102 between the blades 111 and 112. The position of the sheet when so disposed is indicated in Fig. 5. Blades 111 and 112 are caused to successively swing into juxtaposition with table 102 to fold over the portions of the sheet adjacent the score marks or creases therein. This is accomplished in the following manner:

Journaled in two bearings 115 and 116 attached to the table 102 is a shaft 117. This shaft is also journaled in bearings formed in the frame members 15 and 16 which have not been illustrated in the drawings. Shaft 117 carries two spiral cams 118 and 119 which are attached thereto by means of screws 121. These two cams are adapted to engage two arms 122 and 123 secured to the ends of the shafts 108 and 109 by means of screws 124. The shaft 117 rotates in a clockwise direction as viewed in Fig. 2 and the cams 118 and 119 engage the arms 122 and 123 and swing the shafts 108 and 109 and the blades 111 and 112 secured thereto toward one another and in juxtaposition with the table 102. The blades 111 and 112 are normally urged toward the supports 113 and 114 by means of torsion springs 125 which encircle the shafts 108 and 109 between the rear bearing 104 and arm 122 and between the rear bearing 105 and the arm 123. These springs are anchored to the said bearings and to the arms and maintain the said arms in contact with the cams 118 and 119 when the cams are in position to be engaged thereby. The cam 118 is constructed with a notch 126 and the cam 119 is likewise constructed with a notch 127. These notches serve to partly release the blades 111 and 112 for a purpose to be presently more fully described.

The shaft 28 of the invention serves as a drive shaft and is provided with a crank 128 by means of which the same may be rotated. This shaft has attached to it a sprocket wheel 129. A chain 131 passes over this sprocket wheel and over another sprocket wheel 132 fast to the shaft 117. By means of this construction, shaft 117 is rotated in correspondence with the shaft 28.

The feeding mechanism C is operated in the following manner: Arm 84 extends upwardly above the shaft 88 and has pivoted to it by means of a pintle or bolt 133 a longitudinally extending link 134. This link is pivoted to an arm 135 by means of a similar bolt or pintle 136. The arm 135 is attached to shaft 117 and the link 134 is disposed upon the exterior of the arm 135 so that said arm may make a complete revolution as the shaft 117 revolves. The arm 135 is relatively short, as compared to the distance between the pintle 133 and shaft 82 so that the arm 84 is caused to rock while the arm 135 makes a com-

plete revolution. It will thus be readily comprehended that as shaft 117 rotates, arm 98 is caused to reciprocate and the roller 92 caused to advance the sheets 66 from the stack 65 to the creasing mechanism A.

The pressing mechanism F utilizes the two scoring rolls 32 and 33 which are constructed for the purpose with wide faces 137 and 138. These two rolls are adapted to engage another roll 139 of a length greater than the combined lengths of the faces 137 and 138 of said rolls. The roll 139 is preferably constructed of rubber or some similar resilient material, whereby uniform pressure may be had between the rolls of the pressing mechanism F to procure uniform pressing of the folder portions of the sheet. The roll 139 is attached to a shaft 141 which is journaled in two bearings 142 and 143. These bearings are mounted in two levers 144 and 145 which are identical with the levers 51 and 52 previously referred to. These two levers are mounted for oscillation upon the shaft 53 previously referred to and are held in position longitudinally thereon by means of collars 146. These levers are urged downwardly in a manner similar to the levers 51 and 52 by means of compression coil springs 147 which encircle bolts 148 attached to the cross bar 64. By means of said springs the roll 139 is urged upwardly into engagement with the rolls 32 and 33 to provide suitable pressure between the same.

For the purpose of relieving the pressure between the rolls 26, 27, 32, 33 and 139 a releasing device indicated in its entirety by the reference numeral 150 is employed. This device consists of a rod 149 which is constructed at its ends with offset portions 151 journaled in bearings 152 formed in the longitudinal frame members 15 and 16. One of the offset portions 151 of the rod 149 has attached to it a thumb piece 160 by means of which said rod may be manipulated. When the rod is in the position shown in Fig. 2 the various springs are free to act upon the levers and the rolls are all brought into engagement. When the finger piece 160 is turned and rod 149 rotated through an angle of 180 degrees, all of the levers are raised and the rolls freed from one another. Such construction permits of sliding the rolls for the purpose of adjusting the width of the score lines formed by the creasing mechanism A and also permits of removing paper which is improperly passing through the rolls.

The scored sheet after having been folded by the folding mechanism D is fed by means of feed mechanism E to the pressing mechanism F. This feed mechanism will now be described in detail.

The table 102 is constructed at the center of the same with an offset portion 153 forming a groove 154 in the same. The table 102 is also constructed with an opening 155 in the rearward end thereof which extends up to the bearings 115 and 116 and past the arms 122 and 123 permitting said arms to swing freely. The opening 155 extends into the offset portion 153 of the table 102 as indicated at 156 to receive a pusher device indicated in its entirety by the reference numeral 157. This pusher device comprises a slide 158 disposed below the offset portion 153 of table 102. This slide is slidably mounted between four lugs 161, 162, 163 and 164 which are struck out of the metal of said offset portion and which themselves are offset with respect thereto and disposed below the same. The slide 158 is provided with a depending flange 159. This de-

pending flange has secured to it an upwardly extending plate 165. Plate 165 is provided with two spaced parallel bosses 166 and 167 which are drilled to provide two longitudinal parallel bores, not shown in the drawings. These bosses are further threaded to receive set screws 168. The pusher device 157 includes a pusher plate 169 which is constructed with two rearwardly extending rods 171 and 172. These rods pass through the bores in the bosses 166 and 167 and may be adjustably held in position with respect to said bosses by means of set screws 168. The lowermost portion 173 of this plate is constructed to enter the slot 154 and is so constructed for the purpose of preventing the folded sheet lying upon the table 102 from slipping beneath said pusher plate when the pusher plate is operated. It will be noted that the table 102 is substantially at the locality of tangency of the roll 139 and the rolls 32 and 33. It will thus be readily comprehended that as soon as the pusher device 157 advances the paper to these rolls, that the paper is picked up and progressed through the rolls by means of the friction created between the same. The pusher device 157 is operated by means of a cam 174 which is attached to shaft 117 by means of a screw 175. This cam is spiraled in form and engages the plate 165 between the two bosses 166 and 167. As shaft 117 rotates the cam 174 moves the pusher plate 169 toward the presser mechanism F. A tension coil spring 176 secured at one end to a lug 177 on the end of the slide 158 and at its other end to a lug 178 on the offset portion 163, serves to move the pusher device 157 back to normal position when the cam 174 passes plate 165.

The sheets discharged from the presser device F are collected in the receptacle G previously referred to. This receptacle is constructed with a bottom 181 and spaced parallel side walls 182. These side walls are connected to the bottom by a vertical front wall 183 and an inclined rear wall 184. The receptacle is of such a width as to be easily received between the two frame members 15 and 16 and is so designed that the rear wall 184 thereof may be brought into close proximity to the roll 139. The pressed sheets upon leaving the pressing mechanism F are deposited into receptacle G and the ends of the same slide down the inclined wall 184 into position upon the bottom 181 and upon the last deposited sheet within the receptacle. The receptacle may be easily removed by sliding the same forwardly from its position shown in Fig. 2.

The operation of the invention is as follows: The stack of sheets 65 is placed upon the bottom 68 of magazine B and the end gauge 185 adjusted so that the leading edges of the sheets 66 of the stack come in close proximity to the lip 69 of said bottom. The two side register gauges 72 and 73 are next adjusted so that the sheet is disposed medially of the device. These gauges are so positioned that the friction pads 71 engage the edges of the sheets and exert an appreciable amount of pressure upon the same. With the parts so arranged the sheets are firmly held in position. The pressure on the rolls of the creasing mechanism and the pressing mechanism is next released by means of the finger piece 160.

Scoring rolls 26 and 27 are next adjusted so that the creases or score lines formed in the sheet occur at the proper localities. This is accomplished by loosening set screws 42 and 43 and by sliding said rolls to the proper positions

upon shaft 28 and by thereafter tightening said set screws. Rolls 32 and 33 are loose upon the shaft 34 and are slid along said shaft until the V-shaped grooves 31 therein register with the V-shaped ridges 29 on the rolls 26 and 27. The releasing mechanism is now manipulated by turning finger piece 160 until the rod 148 is released from the various levers with which it operates. This creates pressure between the various rolls and the device is now ready to operate.

Upon rotation of the crank 128 the feed mechanism C is operated and the feed roller 92 moves the sheets one at a time out of the stack 65 and brings said sheets in between the rolls 26 and 27 and the rolls 32 and 33. The uppermost sheet indicated by the reference numeral 67 has been shown as just ready to be engaged by these rolls. When the stack 65 is high the uppermost sheets are substantially at the elevation of the points of tangency of the rolls of the creasing mechanism A. As the stack becomes reduced in height, the uppermost sheets engage the lip 69 and are directed upwardly into proper position to be engaged by the creasing mechanism. As soon as the scoring rolls catch the sheet being fed by the feed mechanism C, the rate of travel of the sheet is increased and the roller 92 is moved away from the blade 97 of the feed mechanism. When this occurs the roller travels freely and the sheet is progressed through the creasing mechanism without interference from the feed mechanism. As the sheets pass through the creasing mechanism, score lines or creases are formed at the proper localities in the sheets and the sheets so formed are deposited upon the table 102 between the blades 111 and 112 of the folding mechanism D. One such sheet is shown in Figs. 5 to 10 and is indicated by the reference numeral 191. This sheet is scored along two lines 192 and 193 forming two flaps 194 and 195 at the sides of the sheet and an intermediate portion 196 between said flaps. Due to the weight of the sheet the intermediate portion 196 rests upon the table 102 and the two flaps 194 and 195 rest upon the blades 111 and 112 and upon the supports 113 and 114. As the shaft 28 rotates, shaft 117 travels with it and cam 118 is first brought into action. This cam engages the arm 122 and moves the blade downwardly, folding the flap 194 upon the intermediate portion 196 of sheet 191. The relation of the parts after this operation is completed is shown in Fig. 6. In this figure it will be noted that the flap 194 rests upon the intermediate portion 196 and that the flap 195 still remains in its original position. In the folding of the flap 194 it frequently occurs that the portion of the sheet adjacent the score line 193 is moved toward the shaft 109 to such an extent that the blade 112 could not effectively fold over flap 195. For this reason, it is necessary that the paper be permitted to travel back toward the shaft 109 if the paper had so traveled during the folding of flap 194. To accomplish this result, the cam 118 is constructed with the notch 126 previously referred to. When this part of the cam engages the arm 122, blade 111 is slightly released and the said blade and flap 194 raised upwardly somewhat as shown in Fig. 7. Upon further rotation of shaft 117, cam 119 comes into action and engages the arm 123 moving the said arm and turning blade 112 about shaft 109. This occurs until the parts become disposed, as shown in Fig. 8. In this position the flap 195 overlies the flap 194 and the blade 111. Further rotation 75

of shaft 117 releases cam 118 from arm 122 and the spring 125 returns the blade 111 to normal position. During such movement, the blade lifts the flap 195, as shown in Fig. 9 until the said blade becomes released therefrom. Upon return of blade 111 to normal position, the portion of cam 119 having the notch 127 engages the arm 123 and also slightly releases the blade 112. The position of the parts after this operation has been completed is shown in Fig. 10. In order that the sheet be moved from the folding mechanism D to the pressing mechanism F, it is necessary that the pressure on the sheets brought about by blade 112 be slightly released. Cam 174 now comes into action and commences to move the pusher device 157 forwardly. The portion 173 of pusher blade 169 now engages the folded sheet and advances the same along until the said sheet is engaged by the presser mechanism F. The sheet then passes between the rolls 32, 33 and 139 and is discharged into the receptacle G. The machine is so timed that as soon as the creased sheet leaves the creasing mechanism A, the feed mechanism C commences to move rearwardly. The rolls 26 and 27 are also of such diameter that a single revolution of the same will cause the maximum size sheet to pass completely through the creasing mechanism.

Although I have described the invention as operated by hand, it can readily be comprehended that an electric motor may be used and suitable reduction gearing employed, whereby the shaft 128 may be continuously driven.

The advantages of my invention are manifest. An extremely simple and practical device is provided by means of which sheets may be folded for the purpose of insertion into envelopes. With my machine the sheets are quickly and accurately folded so that the same may be easily inserted into the envelope. The device can be operated either by hand or by power and is of suitable dimensions so that the same can be readily used in an office or any other desirable place of business. The device will handle any type of sheets such as are now used in correspondence and the same may be used to make one or two folds as desired. By means of the pressure mechanism used the folded sheets come out relatively flat so that the same are easy to insert in the envelopes. The device is practically foolproof and will not readily get out of order. By manipulation of the release the pressure on the rolls can be removed so that adjustment of the device is readily accomplished and removal of sheets from between the rolls is easily accomplished when the occasion demands. The receptacle for the folded sheets is readily removed from the machine when the same becomes filled.

Changes in the specific form of my invention, as herein disclosed, may be made within the scope of what is claimed without departing from the spirit of my invention.

Having described my invention, what I claim as new and desire to protect by Letters Patent, is:

1. In a folding machine, a pair of scoring rolls, a folding mechanism adjacent said scoring rolls, said scoring rolls delivering scored sheets to said folding mechanism, a presser roll cooperating with one of said scoring rolls, and means for feeding the sheets from said folding mechanism to said second named scoring roll and said presser roll.

2. In a folding machine, a creasing mechanism, a pressing mechanism in close proximity thereto, a folding mechanism extending away from said

creasing mechanism and said pressing mechanism, said creasing mechanism discharging scored sheets to said folding mechanism, and feed means for reversing the direction of travel of the sheets and removing sheets from said folding mechanism and delivering them to said pressing mechanism.

3. In a folding machine, a table on which sheets to be folded are deposited, a pair of spaced parallel shafts having their axes close to said table, blades carried by said shafts and movable from extended positions to positions in close proximity to said table, arms secured to said shafts, an operating shaft and cams on said operating shaft and engaging said arms, said cams being arranged on said operating shaft to procure successive movement of said arms to successively swing said blades into engagement with the portions of the sheet deposited thereon for successively folding said portions of the sheet one upon the other, a slide guided for movement parallel with said blades and blade shafts, a pusher plate carried by said slide and engaging the folded sheet to move the same longitudinally along said table, and means on said operating shaft for moving said pusher plate.

4. A folding machine comprising a framework, a magazine for sheets carried by said framework and disposed near one end thereof, a creasing mechanism intermediate the ends of the machine, means for feeding sheets from the magazine to said creasing mechanism, a folding mechanism at the other end of the machine and carried by said frame and to which creased sheets are delivered from said creasing mechanism, a pressing mechanism carried by said frame and disposed in proximity to said creasing mechanism, feeding means for reversing the direction of travel of the sheets and for delivering the folded sheets to the pressing mechanism, and a receptacle for folded sheets positioned below said magazine and to which the pressed sheets are delivered.

5. In a folding machine, a horizontal support, a creasing mechanism adjacent one end of said support and discharging creased sheets on said support, means on said support for folding the creased sheets delivered thereto, a pressing mechanism at the same end of the support as said creasing mechanism, and feed means for feeding the folded sheets from the support to said pressing mechanism.

6. In a folding machine, a revolute member having a concentric circular ridge thereon, a cylindrical roll having a circular concentric groove in the periphery thereof contacting with said ridge to crease sheets passing between said ridge and groove, folding means adjacent said revolute member and roll for folding the sheets creased thereby, a second roll having a cylindrical surface contacting with the cylindrical surface of said first roll to press sheets passing therebetween, and means for feeding folded sheets from said folding means in between said first and second rolls.

7. In a folding machine, a revolute member having a concentric circular ridge thereon, a cylindrical roll having a circular concentric groove in the periphery thereof contacting with said ridge to crease sheets passing between said ridge and groove, folding means adjacent said revolute member and roll for folding the sheets creased thereby, a second roll constructed of a resilient material and having a cylindrical surface contacting with the cylindrical surface of said first

roll to press sheets passing therebetween, and means for feeding folded sheets from said folding means in between said first and second rolls.

8. In a folding machine, a magazine for sheets, a receptacle for folded sheets beneath said magazine, folding means to one side of said magazine and receptacle, feed means for feeding the sheets away from the magazine to the folding means, and feed means for feeding the folded sheets from the folding means back toward the magazine and into the receptacle.

9. In a folding machine, a horizontally extending frame, a magazine for sheets at one end of the frame, creasing rolls intermediate the ends of the frame, a folding device at the other end of the frame and on the opposite side of said creasing rolls, means for feeding sheets from the magazine to the creasing rolls, said creasing rolls delivering the creased sheets to said folding device, said magazine being elevated, and means for feeding the folded sheets from said folding device back underneath said magazine.

10. In a folding machine, a table on which sheets to be folded are deposited, a pair of spaced parallel shafts having their axes close to said

table, blades carried by said shafts and movable from extended position to positions in close proximity to said table to fold sheets placed upon said blades and table, an operating shaft disposed near the ends of said first shafts, means on said operating shaft for moving said blades to fold the sheets, an ejecting member, means for guiding said member for movement in a direction parallel with said first shafts to eject a folded sheet from said blades and means operated by 10 said operating shaft for actuating said ejecting member.

11. In a folding machine, a shaft, two revolute members on said shaft, each of said members having a circumferential circular ridge, means 15 for adjustably securing one of said members to said shaft at various positions along said shaft, a second shaft parallel with said first shaft, two rollers on said second shaft, grooves in said rollers cooperating with said ridges, and means for 20 adjustably securing one of said rollers to said shaft at positions along the shaft corresponding to those of the adjustable revolute member.
